UNITED STATES PATENT OFFICE

128,660

DESIGN FOR A TOILET MIRROR

Walter J. Bohn, Toledo, Ohio, assignor to The Acme Specialty Manufacturing Company, Toledo, Ohio, a corporation of Ohio

Application March 28, 1941, Serial No. 99,981

Term of patent 7 years

To all whom it may concern:

Be it known that I, Walter J. Bohn, a citizen of the United States and resident of Toledo, county of Lucas, and State of Ohio, have invented a new, original, and ornamental Design for a Toilet Mirror, of which the following is a specification, reference being had to the accompanying drawing, forming a part thereof.

In the drawing, Fig. 1 is a front perspective view of a toilet mirror showing my new design; Figs. 2 and 3 are front and side elevations, respectively, thereof, and Fig. 4 is a top plan

view thereof taken in the direction of the arrow in Fig. 3.

The tubular member exposed through the front opening in Fig. 1 is a diffusing light source such as an electric incandescent lamp bulb.

The dominant features of the design reside in the portions shown in full lines.

I claim:

The ornamental design for a toilet mirror, substantially as shown and described.

WALTER J. BOHN.
